SIDE DELIVERY RAKE

Filed Jan. 20, 1948

UNITED STATES PATENT OFFICE

2,514,561

SIDE-DELIVERY RAKE

Charles J. Scranton, La Porte, Ind., assignor to
 Allis-Chalmers Manufacturing Company, Milwaukee, Wis., a corporation of Delaware

Application January 20, 1948, Serial No. 3,300

6 Claims. (Cl. 56—377)

1

This invention relates generally to hay rakes, tedders and the like and is more particularly concerned with the reel structure usually incorporated in an apparatus of this type.

And the present invention is directed toward and has as an object the provision of a reel structure incorporating features of improvement as to construction and mounting affording a material reduction in the time, effort and skill required to assemble or disassemble same.

Another object and feature of this invention is the provision of a reel structure utilizing interchangeable parts and detachable reel-bar bearing mountings permitting these bars to be separately removed and replaced or serviced, as required.

Still another object of this invention is the provision of a reel structure incorporating improved features of construction for reel bars having crank extensions adapted to be journaled in peripheral bearing portions of a spider element whereby the reel bars may be assembled on the reel structure either before or after the spider element has been operatively mounted thereon.

A further object of this invention is to provide a durable reel structure incorporating features of simplification as to construction and assembly affording material advantages as to cost of manufacture and maintenance.

The construction, assembly and operation of apparatus embodying the invention will become readily apparent as the disclosure progresses and particularly points out additional objects and advantages considered of special importance. And accordingly, the present invention may be considered as comprising constructions, combinations and subcombinations of elements, including parts thereof, as is hereafter more fully set forth in the detailed description and appended claims. And for a better understanding of the construction, assembly and operation of an illustrative apparatus, attention is directed to the accompanying drawing illustrating but one embodiment of the invention and in which:

Fig. 1 is a plan view of a rake reel assembly and mounting with certain parts omitted in the interest of simplicity;

Fig. 2 is a view in elevation of the left end of the structure shown in Fig. 1;

Fig. 3 is a view in elevation of the right end of the structure shown in Fig. 1 with parts omitted in the interest of simplicity; and

Fig. 4 is an enlarged longitudinal vertical section through the right end of the reel assembly shown in Fig. 1 with parts further cut away to better show the construction.

2

As best seen in Figs. 1, 2 and 3, the reel mounting frame structure comprises parallel front and rear side members 1 and 2, respectively, having their left hand end portions interconnected by a bar 3, having the right hand end portions connected by an angle member 4 and having longitudinally spaced opposed portions interconnected by bracket forming stripper bars 6. This frame structure also includes a rigid beam 7 which has its rear end fixedly secured to a plate 8 attached in bracing relation to the rear left hand corner of the frame structure and which extends forwardly over the frame structure in upwardly arched oblique relation thereto. The mid portion 15 of the front and rear frame members are interconnected by an upwardly arched brace 9 having its forward end attached to member 1 in underlying relation with respect to beam 7. A forwardly projecting beam 11 has its rear end fixedly secured to a right hand extension of member 2 and extends forwardly therefrom beneath front member 1 in spaced underlying relation thereto. Angle member 4 also extends forwardly beneath member 1 in underlying spaced relation thereto 25 and is secured therewith by means of a spacer tube 12 through which passes the adjacent end of a basket forming bar 6, the latter having a threaded end portion which passes through an aligned aperture in front member 1 and is fixed thereto by means of a nut 13. The forwardly extending beam 11 may also be secured to the overlying portion of member 1 in substantially the same manner as just described with respect to angle member 4. The left side of the reel 35 frame includes a U-shaped bearing supporting bracket 14 secured in depending relation to the mid portion of bar 3, the latter being braced by a member 16 connecting an intermediate portion thereof with a portion of beam 7 spaced from plate 8 and rear member 2. The right side of the reel frame also includes a U-shaped bearing support bracket 17 (see Fig. 3) secured in depending relation to a portion of angle member 4 intermediate its point of connection with front and rear side frame members 1 and 2. A brace member 15 connects the reel bearing supporting portion of angle member 4 with an opposed portion of beam 11. The frame structure just described is adapted to be supported in part by a pair of ground engaged wheels (not shown) and in part by a forwardly extending draft structure (not shown) including as elements thereof the forwardly converging beam members 7 and 11.

A pair of opposed reel stub shafts 18 and 19 50 are rotatably mounted in bearings 21 and 22, re-

spectively, including rectangular housing structures having grooved opposite sides guidedly engaged with the inner opposed edges of U-shaped brackets 14 and 17, respectively. These bearing structures are suspended for vertical adjustment relative to brackets 14 and 17 by means of chains, cables, or the like, 23 and 24 which pass over suitable frame mounted pulleys or equivalent guiding elements 26 and 27, respectively, and are adapted to be connected with a suitable conventional adjusting means such as levers or the like (not shown). The opposite ends of stub shafts 18 and 19 are united and in effect made continuous by an interconnecting tube shaft 28 fixedly secured in telescoping relation to the opposite ends of these stub shafts in any suitable manner such as by pins, cap screws or the like 29 as shown in Fig. 4. The portion of stub shaft 18 adjacent bearing 21, the mid portion of tube shaft 28, and the portion of stub shaft 19 adjacent bearing 22 each has a similar reel bar supporting disc 31 keyed or otherwise secured thereto, these discs each presenting a peripheral flange 32 generally parallel to the axis of shaft 28. A plurality of similar tine carrying reel bars 33 are detachably secured to the outer peripheral surfaces of flanges 32 in circumferentially spaced relation with respect to each other by means of similar bearing and strap elements 34 and 36, respectively. As shown reel bar 33 comprises a pair of tubular members 25 and 30 secured in telescoping relation to opposite ends of a stub shaft 35 in any suitable manner such as described in relation to stub shafts 18 and 19. The left ends of each tubular member 25 are secured in telescoping relation to a stub shaft 45 in a conventional manner and the right ends of each tubular member 30 are likewise secured to a crank extension 39. The left end, the right end and the mid portion of each reel bar 33, that is stub shafts 45, 35 and crank extension 39, respectively, are rotatably journaled in similar bearing structures 34.

The flanges 32 of discs 31 are each provided with a series of circumferentially spaced holes 37 therethrough corresponding in number to the bars 33 to be mounted thereon. Each bar 33 has its opposite ends and mid portion journaled in bearings 34, these bearings each including a housing structure having a base portion presenting a depending positioning boss adapted to be inserted in a hole 37 in disc flange 32. These bearing structures are also provided with a top surface having a pair of circumferentially extending spaced parallel ribs 20 forming a groove in which is disposed a strap element 36 including oppositely extending feet portions 38 which are bolted or otherwise fixedly secured to the outer peripheral surface of flange 32 on each side of a bearing structure as best shown in Fig. 3.

Each reel bar 33 is provided with a crank extension 39 rotatably journaled in opposed peripheral bearing portions 41 of a control spider 42 having a hub part 40 provided with a circumferentially grooved inner surface 43 coaxial with respect to the crank receiving bearing portions thereof. Spider 42 is rotatably supported on a coaxial group of ribbed rollers 44 detachably mounted on a member 46 which is in turn eccentrically mounted on stub shaft 19 preferably between bearing 22 and the adjacent reel bar mounting disc 31 to turn relative thereto. The ribbed surfaces of rollers 44 are complementary to and supportingly engage the inner grooved surface 43 on spider hub 40 thereby retaining the spider, rollers, and the roller carrying mem-

ber in correct operative relation. In this connection it should be noted that the depth of the groove in surface 43 is greater than the height of the ribs on rollers 44. Member 46 may be turned to and retained in any selected position by means of an arm 47 having its remote end pivotally connected with a forwardly extending rod 48 which in turn is operatively connected with an actuating means such as a lever or the like (not shown). Movement of member 46 varies the angular position of spider 42 with respect to the reel disc bars 33 and thereby the angular position of these bars and of the tines mounted thereon, the tine bars responding to a movement of member 46 and spider 42 by turning in their bearing structures 34 detachably secured to the flanges 32 on reel bar supporting discs 31.

The outer end of stub shaft 19 is provided with a reel drive clutch assembly comprising an element 49 keyed to shaft 19 for rotation therewith and a sprocket-wheel element 51 rotatable relative to element 49 and releasably engaged thereto by means of coacting teeth 52 and a compression spring 53 surrounding shaft 19 and retained thereon in operative engagement with sprocket element 51 by means of spring seats 54 and nuts 56. The arrangement of these clutch elements is such that elements 49 and 51 are normally engaged to drive shaft 19 but are automatically disengaged to prevent damage whenever the driven load becomes excessive. Sprocket element 51 is adapted to be driven through a chain connection 57 with a conventional drive sprocket (not shown).

It should now be obvious that tine bars 33 may be severally attached to and removed from reel bar disc 31 simply by removing the retaining strap elements 36 and withdrawing the journal portions of crank extensions 39 from spider mounted bearings 41. This withdrawal of the crank extensions from the spider is readily effected since the left hand ends of the tine bars are devoid of crank extensions and, therefore, these bars may be moved longitudinally to the left upon disconnecting strap elements 36. These features of construction materially reduce assembling and servicing costs and in addition afford a structure wherein the reel bars and the reel control spider may be severally assembled and removed as desired with a minimum of time and effort. For example, in assembling an apparatus constructed in accordance with this invention (assuming reel bars 33 have been fabricated in the manner hereinbefore set forth), the journal portions of tine bar crank extensions 39 are then inserted in spider bearings 41, assuming the latter is already mounted on stub shaft 19, and the assembly is completed by bolting the straps 36 to the flanges 32 of the reel bar supporting discs 31 as previously indicated. Obviously spider 42 may be positioned on the journal portions of crank extensions 39 after bars 33 have been secured to reel discs 31.

In general the construction herein shown and described embodies features directed toward accomplishing, in whole or in part, one or more of the afforded aforementioned objects and advantages, and it should be therefore understood that it is not intended to limit the invention to the exact construction herein shown and described for purposes of illustration as various modifications, within the scope of the appended

claims, may occur to persons schooled in the art.

It is claimed and desired to secure by Letters Patent:

1. In a rake or the like embodying a frame structure rotatably mounting a reel shaft, a plurality of disc elements mounted on said shaft in axially spaced relation for rotation therewith, said elements each including a coaxial flange having circumferentially spaced bearing housing positioning and supporting portions similarly arranged concentrically with respect to the axis of said reel shaft, a plurality of bars each having longitudinally spaced portions thereof rotatably journaled in bearings axially spaced apart distances conforming with the axial spacing of said elements, said bearings each including a housing having a base portion shaped for positioning engagement with the bearing housing supporting portions of said flange, and means detachably securing the housings of the bearings on each reel bar to the axially aligned bearing housing positioning and supporting portions presented by the flanges on said elements.

2. In a rake embodying a frame structure rotatably mounting a reel shaft, a plurality of disc elements mounted on said shaft in axially spaced relation for rotation therewith, said elements each including a laterally projecting coaxial peripheral flange having circumferentially spaced similarly arranged boss receiving apertures therein, a plurality of toothed reel bars having longitudinally spaced portions thereof rotatably journaled in bearings axially spaced apart distances conforming with the axial spacing of said elements, said bearings each including a housing having a base portion complementary to the outer surface of said flange and provided with a boss adapted for insertion in a boss receiving aperture in said flange, and means detachably securing the housings of the bearings on each reel bar to the axially aligned bearing housing positioning and supporting portions afforded by the flanges on said elements.

3. In a rake embodying a frame structure rotatably mounting a reel shaft, a plurality of disc elements mounted on said shaft in axially spaced relation for rotation therewith, said elements each including a laterally projecting coaxial flange having circumferentially spaced similarly arranged boss receiving apertures therein, a plurality of reel bars having longitudinally spaced portions thereof rotatably journaled in bearings axially spaced apart distances conforming with the axial spacing of said elements, said bearings each including a housing having a base portion complementary to the outer surface of said flanges adjacent said apertures and provided with a boss adapted for insertion in a boss receiving aperture therein, said housings also each having a top portion presenting a pair of circumferentially extending laterally spaced external ribs forming a groove therebetween, and a strap element disposed in the groove of each housing and having oppositely extending feet portions detachably secured in abutting relation against external portions of the flange on each element adjacent opposite sides of the bearing housing engaged therewith.

4. In a rake embodying a frame structure rotatably mounting a reel shaft, a plurality of elements mounted on said shaft in axially spaced relation for rotation therewith, said elements presenting coaxially arranged and longitudinally aligned parts adapted to position and sup-

port a bearing housing thereon, a reel control spider having fixed therein circumferentially spaced, coaxial reel-bar crank extension receiving bearings, means rotatably mounting said spider adjacent the outer side of an end one of said elements with the bearings therein disposed adjacent the bearing positioning and supporting parts of said elements, a plurality of reel bars having longitudinally spaced portions thereof rotatably journaled in bearings axially spaced apart distances corresponding to the axial spacing of said elements, said bearings each including a housing having a base portion shaped for positioning engagement with the bearing supporting portions of said parts, said reel bars each including a crank extension terminating in a journal portion insertable into and withdrawable from the crank extension receiving bearings in said spider, and means detachably securing the housings of the bearings on each reel bar to the longitudinally aligned parts presented by said elements with the journal portions of the crank extensions on said bars disposed in the crank receiving bearings in said spider.

5. In a rake embodying a frame structure rotatably mounting a reel shaft, a plurality of elements mounted on said shaft in axially spaced relation for rotation therewith, said elements each presenting circumferentially spaced parts similarly arranged concentrically with respect to the axis of said shaft and adapted to position and support a bearing housing thereon, a reel control spider having fixed therein circumferentially spaced, coaxially arranged reel-bar crank extension receiving bearings, means removably, rotatably mounting said spider adjacent the outer side of an end one of said elements with the bearing therein disposed adjacent the bearing housing positioning and supporting parts of said end element, a plurality of toothed reel bars having longitudinally spaced portions thereof rotatably mounted in axially spaced bearings axially spaced apart distances conforming with the axial spacing of said elements, said bearings each including a housing having an exterior portion adapted to engage a bearing positioning and supporting portion of said parts, said reel bars each including a crank extension terminating in a journal portion insertable into and withdrawable from the crank extension receiving bearings in said spider, and means detachably securing the housings of the bearings on each reel bar to the longitudinally aligned parts presented by said elements with the journal portions of the crank extensions on said bars disposed in the crank receiving bearings in said spider.

6. In a rake embodying a frame structure rotatably mounting a reel shaft, a plurality of disc elements mounted on said shaft in axially spaced relation for rotation therewith, said elements each including a laterally projecting peripheral flange generally parallel to the axis of said flange and having circumferentially spaced similarly arranged boss receiving apertures therein, a reel control spider mounted for rotation in adjacent parallel relation to an outer side of an end one of said elements, said spider having peripheral portions provided with circumferentially spaced bearings adapted to receive shaft portions generally parallel to the axis of said shaft, a plurality of toothed reel bars having longitudinally spaced portions thereof rotatably mounted in bearings axially spaced apart distances conforming to the axial spacing of said elements, said bearings

each including a housing having a base portion complementary to the outer surface of said flange and provided with a boss adapted for insertion in the boss receiving aperture therein, said reel bars each including a crank extension having a journal portion insertable into and withdrawable from a bearing in said spider, and said housings also each having a top portion presenting a pair of circumferentially extending, laterally spaced external ribs forming a groove 10 therebetween, and means detachably securing the housings of the bearings on each reel bar to axially aligned portions of said flanges with the boss on each housing disposed in a positioning aperture in the underlying flange comprising a strap element disposed in the said groove in each bearing housing and having oppositely extending

feet portions detachably secured in abutting relation against external portions of the flange in housing clamping relation thereto.
